(57) **CLAIM**

The ornamental design for a power wand, as shown and described.

DESCRIPTION

Cross-reference is made to U.S. patent application Ser. No. 15/354,463 titled "Power Wand and Method of Use," filed on Nov. 17, 2016, and is expressly incorporated herein by reference.

FIG. 1 is a perspective view of a power wand design; FIG. 2 is a second perspective view of the design of FIG. 1; FIG. 3 is a front view of the design of FIG. 1; FIG. 4 is a rear view of the design of FIG. 1; FIG. 5 is a right side view of the design of FIG. 1; FIG. 6 is a left side view of the design of FIG. 1; FIG. 7 is a top view of the design of FIG. 1; and, FIG. 8 is a bottom view of the design of FIG. 1. The broken lines illustrating portions of the power wand form no part of the claimed design.
